UNITED STATES PATENT OFFICE.

MARTIN D. WATROUS, OF ANSONIA, CONNECTICUT.

MACHINE FOR APPLYING TIPS TO GARMENT-STAYS.

1,139,608.

Specification of Letters Patent. Patented May 18, 1915.

Application filed September 1, 1911. Serial No. 647,299.

To all whom it may concern:

Be it known that I, MARTIN D. WATROUS, a citizen of the United States, residing at Ansonia, in the county of New Haven and 5 State of Connecticut, have invented new and useful Improvements in Machines for Applying Tips to Garment-Stays, of which the following is a specification.

This invention relates to improvements in 10 machines for applying tips to stays for corsets or other articles of apparel, and it proposes a machine which automatically applies a tip to each end of the stay and wherein the stay is fed in one direction with 15 relation to one tip magazine and tip applying instrumentality and in an opposite direction with relation to a second tip magazine and tip applying instrumentality, the operations thus broadly stated being similar 20 to the operations of the machine shown in my prior U. S. Patent, No. 699,599, of May 6, 1902.

The primary object of the present invention is to improve the organization and construction of the instrumentalities for effecting the operations referred to, to secure the advantages of greater compactness and simplicity and of relative lightness and ease of operation.

30 The invention also proposes an improved mechanism for feeding the tips to the tip magazine.

An embodiment of the invention is illustrated by way of example in the accompanying 35 drawings, wherein:—

Figure 1 is a side elevation of the improved tip applying machine. Fig. 2 is a top plan view thereof. Fig. 3 is an end elevation thereof. Fig. 4 is a detail diagrammatic side elevation to show more particu-

larly the relation and operation of the feed and tip applying rolls. Fig. 5 is a detail sectional view illustrating the construction of the tip hopper and its appurtenances.

40 Fig. 6 is a detail diagrammatic end elevation to show more particularly the relation between the belt trough and the rolls adjacent thereto, and Fig. 7 is a detail perspective view illustrating an adjustable wall which 45 may be employed in connection with the belt trough.

Similar characters of reference designate corresponding parts throughout the several views.

50 The operating parts are supported from a suitable base 1 and are driven through suit-

able gearing from a transverse shaft 2 which carries a loose belt pulley 3 and a suitable clutch 4.

The operations of applying the tips are 60 effected by an upper pair of rolls 5 and 6 and by a lower pair of rolls 7 and 8. In the embodiment shown the rolls 6 and 7 are mounted on the shaft 2 and are preferably integral. The stays are fed in one direction 65 between the rolls 5 and 6 and in an opposite direction between the rolls 7 and 8, a tip being applied at one end thereof by the rolls 5 and 6 and at the opposite end thereof by the rolls 7 and 8. With regard to the direction 70 of movement of the stays through the machine, a tip magazine 9 is located in advance of the rolls 5 and 6 and a tip magazine 10 is located in advance of the rolls 7 and 8. In addition to the tip applying rolls and the 75 magazines the machine includes stay feeding instrumentalities which comprise a pair or rolls 11 and 12 for passing the stays across the lower end of the magazine 9 and between the rolls 5 and 6; a pair of rolls 13 and 14 for passing the stays which have been acted on by the rolls 5 and 6 across the other tip magazine 10 and between the rolls 7 and 8; and means for transferring the 80 stays from the rolls 5 and 6 to the rolls 13 and 14, the means shown consisting of a pair of rolls 15 and 16 which receive the 85 stays from the rolls 5 and 6 and a belt 17 upon which the stays discharged by the rolls 15 and 16 fall and by which said stays are 90 carried to the rolls 13 and 14. The rolls 15 and 16 have the same relation to the rolls 13 and 14 that the rolls 5 and 6 have to the rolls 7 and 8, the rolls 16 and 13 being mounted on the same shaft and being, by preference, 95 integral.

The belt 17 passes over pulleys 18 and 19, the shafts of which are supported by an arm 20 which is secured to the table 1 or to a part carried by said table. The bearing in which the shaft of the pulley 19 is journaled is mounted in a slot 21 at the outer end of said arm and may be adjusted for the purpose of regulating the tension of said belt.

100 It is not deemed necessary to illustrate or describe in detail the gearing by which the several rolls referred to are driven, it being considered sufficient to state that a suitable train, designated generally by the numeral 110 22 and actuated by the shaft 2, is provided to effect the rotation of the rolls in the

proper relative directions and at a uniform rate of speed. It may be noted, however, that the shaft of the pulley 18 is geared to this train in such manner that the belt 17 moves at twice the surface speed of the rolls in order that sufficient friction may be developed to insure the movement of the stays with the belt as they fall upon the latter.

The action of the instrumentalities above described is facilitated by various appurtenances which comprise a suitably supported stay guide 23 located in advance of the rolls 11 and 12 and having a tapering channel or throat through which the stays pass; a table 24 located under the magazine 9 and suitably spaced from the latter, the table 24 being provided with a spring 25 for preventing the displacement of the tip from the end of the stay as the latter passes across said table to the rolls 5 and 6; a stay guide 26 located in advance of the rolls 15 and 16 and having a channel which tapers toward said rolls and through which the stays pass; a belt trough 27 suitably supported from the frame of the machine and from the arm 20; a stay guide 28 located in advance of the rolls 13 and 14 and serving to pass the stays from the belt 17 to said rolls; and a table 29 located under the magazine 10 and suitably spaced from the latter, the table 29 being provided with a spring 30 for preventing the displacement of the tip from the end of the stay as the latter passes across said table to the rolls 7 and 8. The belt trough 27 is of the same length as the upper run of the belt 17, overlying the latter and its walls have a relatively downward taper and are separated at their lower edges by a longitudinal slot 31 of a width to accommodate a single stay. The belt 17 passes immediately under the slot 31 and the walls of the latter form a guide for the stay as it moves with said belt. If desired, an adjustable stop wall 32 (Fig. 7) may be used in connection with the trough 27 to limit the backward movement of the stays as they are discharged by the rolls 15 and 16. The wall 32 is shaped to conform to the cross section of the trough 27 and fits transversely within the same, being secured to a wall of the trough by a suitable clamp 33.

The tip feeding mechanism includes the magazines 9 and 10 above described, a rotatable hopper 34, and gooseneck extensions 35 which are formed at the upper ends of the magazines 9 and 10 and project into the hopper. The support for the hopper comprises a standard 36 (shown in dotted lines) which is attached to a suitable part of the framing of the machine and terminates at its upper end in an annular platform 37 which has an axially extended flange 38. The hopper 34 has a substantial U-shape in cross section and surrounds the flange 38. To the underface of the hopper a spur wheel

39 is attached which rests and is rotatable upon the platform 37. The standard 36 has an arm 40 which supports a shaft 41 upon which is mounted a spur wheel 42, which is driven from the train 22, and a bevel pinion 43.

The platform 37 has an extension 44 which furnishes support for a vertical shaft having at its lower end a bevel pinion 45, meshing with the pinion 43, and at its upper end a pinion 46 meshing with the spur wheel 39. The goosenecks 35 have a torsional as well as a downward curvature and taper to a point whereby as the hopper revolves the tips will be readily and continuously fed up the goosenecks until they align with the vertical portions of the magazines at which time they will descend by gravity through the latter.

To insure the accurate transfer of the stays to belt 27, there may be provided, in connection with trough 27, if desired, a pair of guides 47 and 48, shown in Fig. 1. The former of these guides directs the first tipped end of a stay downward onto the belt, and, also, serves to spring the rear end of the stay quickly thereonto after the stay leaves the rolls 15 and 16. The second guide serves to prevent lateral turning of the stays. Both guides are adjustable, and are supported in the same manner as stop 32, i.e., by means of suitable clamps.

The end of trough 27 adjacent rolls 15 and 16 is adapted to be tilted or raised in the event of the stays becoming clogged, so as to permit the latter to be withdrawn, its opposite end having a pivotal connection with the shaft of pulley 19.

The flange 38 associated with platform 37 is preferably constituted by the upwardly extended portion of an annular sleeve which is encircled by said platform, as shown in Fig. 5.

It is thought that the operation will be readily apparent from the foregoing description. It is to be understood that the present mechanism forms an intermediate element in the production of the stays and that the latter are delivered to the rolls 11 and 12 by suitable means (not necessary to illustrate) from a stay finishing mechanism or from a stay magazine. The tables 24 and 29 are so arranged that a single tip will rest thereon clear of the magazines and as the stays are fed across said tables their then forward ends will engage said tip which under the pressure of the springs 25 and 30 respectively will become fitted upon said end as the stay advances, ready for compression by the rolls 5 and 6 and 7 and 8. As each stay passes from under the magazines, a tip next in order will drop upon the adjacent tables for engagement in the manner set forth by the stay which is next to pass through the machine. Each stay, there-

fore, passes first under the magazine 9 and its then forward end receives a tip which is applied to the stay by the rolls 5 and 6. Thereafter the stay is passed by the rolls 5 and 16 to the belt 17, which reverses the movement of the stay and the latter travels in an opposite direction through the rolls which form the lower pass, its then forward end receiving a stay from the magazine 10 which is applied by the rolls 7 and 8. The latter rolls pass the stays with both ends tipped to a suitable reception or receiving mechanism, (not shown).

Having fully described my invention, I claim:—

1. In a machine of the type set forth, in combination, tip applying rolls arranged in upper and lower passes, a tip magazine arranged in advance of each pass, a belt upon which the stays which have been acted on in the upper pass of said rolls are delivered and by which said stays are carried to the lower pass, and a belt trough located above the upper run of the belt and having at its lower end a slot of a width to accommodate a stay.
2. In a machine of the type set forth, in combination, tip applying rolls arranged in upper and lower passes, a tip magazine arranged in advance of each pass, a belt upon which the stays which have been acted on in the upper pass of said rolls are delivered and by which said stays are carried to the lower pass, a belt trough located above the upper run of the belt and having at its lower end a slot of a width to accommodate a stay, and a transverse wall adjustably associated with the belt trough.
3. In a machine of the type set forth, in combination, tip applying rolls arranged in upper and lower passes, the adjacent rolls being coaxial and the rolls of the upper pass being in a different plane from the rolls of the lower pass, a belt upon which the stays which have been acted on in one pass of said rolls are delivered and by which said stays are carried to the other pass, gearing for driving the rolls and the belt and means associated with the belt to aline the stays passed thereto with the plane of the rolls to which they are to be passed by the belt.
4. In a machine of the type set forth, in combination, tip applying rolls arranged in upper and lower passes, the adjacent rolls being coaxial and the rolls of the upper pass being in a different plane from the rolls of the lower pass, a belt in the plane of the lower pass to deliver stays thereto, and a belt trough arranged above the belt and having at its lower end a slot of a width to accommodate a stay, the belt trough serving to guide the stays discharged by the upper pass upon the belt.
5. In a machine of the type set forth, in combination, tip applying rolls arranged in upper and lower passes, the adjacent rolls being coaxial and the rolls of the upper pass being in a different plane from the rolls of the lower pass, a belt upon which the stays which have been acted on in one pass of said rolls are delivered and by which said stays are carried to the other pass, and means associated with the belt to aline the stays passed thereto with the plane of the rolls to which they are to be passed by the belt.
6. In a machine of the type set forth, in combination, tip applying rolls arranged in upper and lower passes, the adjacent rolls being coaxial and the rolls of the upper pass being in a different plane from the rolls of the lower pass, stay feed rolls arranged in upper and lower passes corresponding to the passes of the first named rolls, a belt upon which the stays which have been acted on in one pass of said rolls are delivered and by which said stays are carried to the other pass and means associated with the belt to aline the stays passed thereto with the plane of the rolls to which they are to be passed by the belt.
7. In a machine of the type set forth, in combination, tip applying rolls arranged in upper and lower passes, the adjacent rolls being coaxial, and the rolls of the upper pass being in a different plane from the rolls of the lower pass, and means for transferring the stays from one pass to the other, and including means for positively alining the stays with the rolls of the pass to which they are to be transferred.
8. In a machine of the type set forth, in combination, tip applying rolls arranged in upper and lower passes, the rolls of the upper pass being in a different plane from the rolls of the lower pass, and means for transferring stays from one pass to the other, and including means for positively alining the stays with the rolls of the pass to which they are to be transferred.
9. In a machine of the type set forth, in combination, tip applying rolls arranged in upper and lower passes, the rolls of the upper pass being in a different plane from the rolls of the lower pass, a belt upon which the stays which have been acted on in one pass of said rolls are delivered and by which said stays are carried to the other pass, and means associated with the belt to aline the stays passed thereto with the plane of the rolls to which they are to be passed by the belt.
10. In a machine of the type set forth, in combination, tip applying rolls arranged in upper and lower passes and in different planes, a belt upon which the stays which have been acted on in the upper pass are

delivered and by which said stays are carried to the lower pass, and a belt trough located above the upper run of the belt and having at its lower end a slot of a width to accommodate a stay.

11. In a machine of the type set forth, in combination, tip applying rolls arranged in upper and lower passes, a belt upon which the stays which have been acted on in the upper pass of said rolls are delivered and by which said stays are carried to the lower pass, a belt trough located above the upper run of the belt and having at its lower end a slot of a width to accommodate a stay, and one or more inclined guides arranged transversely of the belt trough, as and for the purpose set forth.

12. In a machine of the type set forth, in combination, tip applying rolls arranged in upper and lower passes, a belt upon which the stays which have been acted on in the upper pass of said rolls are delivered and by which said stays are carried to the lower

pass, and a belt trough pivotally mounted at its outer end and located above the belt, 25 the trough having along its bottom a slot of a width to accommodate a stay, as and for the purpose set forth.

13. In a machine of the type set forth, the combination with a tip magazine, of a rotatable hopper having a central opening, an annular support for said hopper having an annular flange which engages as a journal in said opening, and a fixed extension at the upper end of the tip magazine which projects through said support and through said flange into the hopper and upon which the tips are continuously fed to the magazine, consequent to the rotation of the hopper.

In testimony whereof I have hereunto set 40 my hand in presence of two subscribing witnesses.

MARTIN D. WATROUS.
